UNITED STATES PATENT OFFICE.

JAMES McDERMOTT, OF BROOKLYN, NEW YORK.

SUSPENDED STAIR-SCAFFOLD.

SPECIFICATION forming part of Letters Patent No. 436,460, dated September 16, 1890.

Application filed May 22, 1890. Serial No. 352,786. (No model.)

To all whom it may concern:

Be it known that I, JAMES McDERMOTT, a citizen of the United States, residing at Brooklyn, county of Kings, State of New York, have 5 invented certain new and useful Improvements in Suspended Stair-Scaffolds, of which the following is a specification.

In the construction of buildings scaffolding must be provided for lathers and plasterers 10 who are working upon the under side of the stairway. On account of the well up which the stairs come it is more or less difficult to erect scaffolding, and it is necessary to provide supports in the walls of the building as 15 well as upon the floors. This always involves more or less expense and delay in the construction of the scaffolding.

The object of my invention is to obviate the necessity of constructing special scaffolding, 20 and I provide a suspended scaffold which is supported directly upon the treads of the stairway, all of which is hereinafter described.

In the accompanying drawings, Figure 1 is a side elevation of one section of my improved 25 suspended scaffold; Fig. 2, a perspective view showing the application of my invention to a stairway.

The suspended scaffold consists of two such sections, such as illustrated in Fig. 1. Each 30 section consists of an upright or standard A, having at the top a horizontal arm or support B, adjustable thereupon by means of the bolt b and bolt-holes b'. The portion B is braced by an adjustable brace B', as is perfectly 35 clear. The part B may also be provided with an extensible portion B², both parts being provided with bolt-holes c for the reception of 40 bolts C, one of which may unite the brace B' with the horizontal arm B. The lower end 45 of the upright A has a corresponding horizontally-projecting arm D, which may be permanently attached thereto. It is provided with a brace D' and an extensible portion D², adjustable, as already described. This apparatus 50 may be made of iron of any suitable strength and character, and, as is obvious, is very cheap and strong.

Fig. 2 shows the application of my invention to a stairway. One section is suspended

50 by the supporting-arm B B², and another section is similarly suspended on one of the treads of the stairway lower down. Scaffolding-boards X are then thrown across the parts D D², and a strong, simple, and perfectly safe scaffolding that may be readily put in place 55 and easily removed is the result. That section of the scaffold which is suspended nearest the lower end of the stairway has the arms B and D closer together than the corresponding arms 60 of the upper section, so that the arms D on 65 the two sections may hold the scaffold-boards in the same horizontal plane.

I claim as my invention—

1. In a scaffolding for stairways, the combination of an upright, a laterally-projecting 65 supporting-arm near the upper end thereof and adapted to rest on the tread of the stairway, a brace secured to the arm extending upwardly therefrom and secured to the upright, and the lower scaffolding-supporting 70 arm secured to the upright below the upper arm.

2. In a scaffolding for stairways, the combination of an upright, supporting-arms projecting in the same direction from the upper 75 and lower ends thereof and disconnected from each other at their outer ends, and braces connecting the arms to the upright.

3. In a scaffolding for stairways, the combination of a pair of uprights, arms projecting in the same direction from the upper and lower ends thereof, and scaffold-boards resting 80 on the lower arms, the arms on one of the uprights being closer together than those on the other upright.

4. In a scaffolding for stairways, the combination of the upright, the arms projecting in the same direction from the upper and lower ends of the upright, braces connecting 85 these arms with the upright, and the extension-pieces on the outer ends of the arms.

In testimony whereof I have hereunto subscribed my name.

JAMES McDERMOTT.
